UNITED STATES PATENT OFFICE.

DAVID C. KLAUSMEYER, OF CINCINNATI, OHIO, ASSIGNOR TO THE CINCINNATI BICKFORD TOOL COMPANY, OF CINCINNATI, OHIO, A CORPORATION OF OHIO.

SAFETY SPINDLE COUNTERBALANCE.

Application filed April 4, 1923. Serial No. 629,852.

To all whom it may concern:

Be it known that I, DAVID C. KLAUSMEYER, a citizen of the United States, and residing at Cincinnati, in the county of 5 Hamilton and State of Ohio, have invented a new and Improved Safety Spindle Counterbalance, of which the following specification is a full disclosure.

This invention relates to drilling machines 10 and it deals primarily with the means for counterbalancing the weight of the spindle and its associated elements whereby the spindle may be readily moved up and down for the purpose of feeding the drill into and 15 out of the work; all while permitting the spindle to rotate.

Heretofore, it has been usual to employ a weight for the purpose of counterbalancing that of the spindle and it has, according 20 to, been necessary to provide space in or adjacent the frame of the machine to accommodate the movement of the weight. Furthermore, when a weight is employed, it has to be of suitable proportions and means 25 must be provided for so that the path of the weight will not be in the immediate proximity of the spindle; all of which has entailed some structural objections. Furthermore, the employment of a weight does 30 not make it possible easily to adjust the degree of the counter-pull on the spindle to meet any particular circumstances of use.

This invention, accordingly, undertakes to render available a very compact and self-contained arrangement suitable for the suspension of a drill-spindle and in which a weight is dispensed with and its functions performed by a coiled spring preferably located in an upper portion of the frame 40 away from the working region of the spindle. Another object of the invention is to combine with the spindle-supporting-means a safety device such that, if the spindle should fail to be supported, the device will 45 operate forthwith to arrest any untoward descent of the spindle.

Another object is so to construct the spring arrangement that the pull on the spindle will be uniform notwithstanding the increase 50 in the tension of the spring when the spindle is in its lower positions; thereby avoiding an objection heretofore raised to the use of springs due to their inability to exactly counterbalance the spindle in all 55 of its positions.

Another object is to provide a very convenient means for adjusting the degree of tension of the spring or for replacing a broken part or for making any other correction necessary to the mechanism. This 60 has always occasioned much trouble in the case of weights because of the difficulty of getting at all parts of the chain and at the points of connection between the chain and the spindle and because of the necessity of 65 propping up both the spindle and the weight, etc.

Other objects and advantages will be in part indicated in the following description and in part rendered apparent therefrom 70 in connection with the annexed drawings.

To enable others skilled in the art so fully to apprehend the underlying features hereof that they may embody the same in the various ways contemplated by this invention, 75 drawings depicting a preferred typical construction have been annexed as a part of this disclosure and, in such drawings, like characters of reference denote corresponding parts throughout all the views, of which:— 80

Fig. 1 is a vertical section taken transversely to that of Fig. 2 showing in side-elevation the counter-balancing device and the safety catch. Fig. 2 is a vertical section of a portion of a drilling machine embodying this invention showing a clutch arrangement enabling the drill spindle to be raised or lowered by hand or by power according to the setting of the levers and showing also the arrangement of the counter-balancing features. Fig. 3 is a plan of a coiled spring such as may be employed. Fig. 4 is an isolated plan of the fusee employed in the counterbalancing device. Fig. 5 is an enlarged fragmentary plan of the emergency check to prevent falling of the drill-spindle. Fig. 6 is an enlarged fragmentary side elevation of said emergency check and Fig. 7 is a front elevation of the isolated pawl. 95

Referring to the drawings, 1 represents a portion of the frame of a drill-head which, in this instance, is provided with guideways 2 and 3 to admit of being shifted bodily along a radial arm or other suitable support. This head 1 has a vertical hole within which is vertically shiftable a sleeve 4. This sleeve does not rotate but may be translated by means of a pinion 17 engaging a rack 16 affixed to one side of the spindle. The pin- 100

ion 17 is carried by a shaft 36 which is keyed to a clutch-member 35 adapted, through a grip-ring 39, to be clutched to a constantly driven worm-wheel 33; the latter receiving its motion from a power shaft not shown.

One or more hand-levers 34 are pivoted to a part rotating with the shaft 36 so that, by grasping the hand-lever and turning it, 10 the shaft 36 may likewise be turned and the sleeve may thus be fed by hand. In order that the power may be engaged with the pinion 17, the hand-lever 34 may be turned about its pivot thereby shifting the cam 37 15 and the pin 38 which controls the clutch. A stop 44 adapted to cooperate with the part 45 on the hand-lever 34 automatically disconnects the power-feed at an adjusted position and a stop 40 cooperating with a 20 shift-key 41 accomplishes the same effect at the limit of the downward stroke of the spindle.

The sleeve 4, which is vertically translatable as aforesaid in the frame 1, carries 25 the spindle 3 which is journaled therein and is restrained against longitudinal movement relative to the sleeve by means of thrust-bearings 5 and 14; the former cooperating with a shoulder provided by the spindle and 30 the latter with an adjustable collar 15, as will be understood.

The weight of the parts is sustained or 35 counterbalanced, without interfering with the vertical movement, by means of a flexible connection here shown as a link-chain 30. This chain is at one end so connected with the spindle as to receive the weight of the parts and, at its other end, the chain is connected with a pull-device adapted to 40 exercise sufficient tension on the chain to counterbalance the downward drag of the spindle and its associated parts. A convenient form of attachment is that shown best by Fig. 1 in which a plate 6 is firmly 45 secured to the upper portion of the sleeve 4 and this plate has a projecting portion 7, the extremity of which is bifurcated to straddle a stationary ratchet-bar 11 having ratchet-teeth 13. It will be seen that, by 50 this arrangement, the sleeve and rack attached thereto are prevented from turning by reason of the engagement between the projecting portion 7 and the stationary ratchet-bar 11. Heretofore the sleeve has 55 been restrained from turning by a stationary projection which, so to speak, had a movement along the sleeve during its rise and descent. By virtue of the present arrangement, the sleeve is thus made available for 60 the use of an additional stop 55 which is complementary in action to the above described stop 40. It will be understood that, when the spindle is merely reversed in direction of rotation, its direction of feed is 65 likewise reversed and the effect of stop 55

is to prevent the spindle from being over-fed upwardly. In prior constructions, the means for preventing the rotation of the sleeve more or less interfered with the employment of a stop at the point 55 and this difficulty has been overcome by the present arrangement.

A pawl 9 is pivoted at 8 to the extension 7 and is urged by a spring 10 towards the ratchet-teeth 13; the object being to effect an 75 immediate and automatic engagement between the pawl 9 and the ratchet-bar 11 in the event that the tension connection 30 either breaks or, for some reason or other, fails to be pulled upwardly with a force sufficient to sustain the weight of the spindle and sleeve. This is accomplished, in this embodiment by providing the pawl 9 with a short arm to which is pivotally attached the lower end of the chain 30. The relation 80 between the pivot 8 and the point of attachment of the chain is such that when the chain exercises sufficient pull it will hold the pawl 9 into its retracted position and out of engagement with the teeth 13. If the tension should be insufficient, however, the spring 10 will be enabled to act and the pawl 9 will prevent any downward movement of the sleeve 4. It will be seen that this safety-catch arrangement is equally applicable 90 whether the tension on the chain 30 be created by an ordinary counterbalancing weight or by the compact spring-mechanism constituting another characteristic of this invention and which will now be described. 100

Preferably the axis of the pin 46 is normally offset with relation to the axis of the pin 8 (see Fig. 6) so that the pawl 9 will be held firmly against a rearward abutment by the pull of the chain and thus prevent it 105 from a tendency to rock or vibrate. This insures that the tooth 49 of the pawl shall normally clear the teeth 13 of the stationary ratchet.

Journaled in the upper portion of the 110 frame 1 is a shaft 18 to which is keyed a worm-wheel 20 which determines the angular position of the shaft 18. Likewise journaled in an upper portion 22 of the frame is a stud 23 which, at one end carries a 115 worm 21 permanently in mesh with the worm-wheel 20 and this stud 23 may be turned by hand by applying a wrench to the squared end 31; thereby enabling the angular position of the shaft 18 to be regulated from the point 21. This being an irreversible drive, it will be apparent that any tendency of the shaft 18 to turn will be restrained by the worm 21 in all positions, although any rotation of the stud 23 will at 120 once effect a corresponding movement in the shaft 18. The purpose of this arrangement is to enable a counterbalancing spring to have its tension adjusted to any desirable degree. This spring is shown by Fig. 3 and 125

is indicated by 24 and at its inner end is attached to the shaft 18 by means of a pin 19. The spring 24 is contained within a rotatable housing 26; it being attached thereto by means of a hooked end 25 engaging a slot in the peripheral wall of the housing, as shown by Fig. 1. The housing 26 is also attached to a member shown by Fig. 4 which is in the nature of a fusee and on the periphery of which winds the chain 30. The periphery of the fusee 27 provides a shallow groove 28 and this groove is of spiral formation so that it progressively increases in distance from the axis of rotation of the fusee. The chain is attached at one end to the end of the groove 28 which is most remote from the axis of rotation, as by means of a pin 29.

It will be perceived that, in consequence of this arrangement, as the spindle is lowered, and as the spiral spring 24 increases in tension, the point on which the chain leaves its drum will be more and more remote from the axis of rotation; in other words, the leverage effect will progressively decrease as the tension of the spring increases and conversely. In this manner, the chain 30 is subjected to a constant tension in all positions of the spindle although the spiral spring has its tension increased as it becomes wound more and more tightly.

It will be perceived that this invention provides a very compact self-contained arrangement, eminently suitable for drilling machines, and which removes from the proximity of the spindle any space occupying elements such as the weight heretofore employed. Also, the invention presents a degree of safety not heretofore attained inasmuch as it is impossible for the spindle or sleeve to fall even though the means normally supporting it should fail and, furthermore, in the event of such a failure, it is a very simple matter to make repairs inasmuch as the connections are immediately accessible and such connections may be established under easy working conditions, to wit, when there is no tension on any of the parts; the means for regulating the tension of the spring being capable of reducing that tension to zero or of increasing it to any desired amount after the connection has been established.

Without further analysis, the foregoing will so fully reveal the gist of this invention that others can, by applying current knowledge, readily adapt it for various utilizations by retaining one or more of the essential characteristics of either the generic

or specific aspects of this invention, and therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A drilling-machine combining a vertically-movable spindle; quick-traverse means therefor; a fusee connected to carry the weight of said spindle; a coiled spring exercising a counter-pull on said fusee; and a safety-latch means for said spindle normally held inoperative by the connection between the fusee and spindle and adapted automatically to arrest the descent of said spindle in case said counter-pull should cease.

2. A drilling-machine combining a spindle; a sleeve having a rack; a pinion engaging said rack; means for turning said pinion either manually to effect a quick-traverse of said sleeve or by power to feed said sleeve; a coiled-spring for counter-balancing said parts; a planar compensator intervening between said spring and said parts for rendering uniform and maintaining in the same plane the pull of said spring on said sleeve and spindle; a worm and worm-wheel for adjusting the normal tension of said spring; and a pawl-and-rack device arranged automatically to become operative to arrest the fall of said spindle in case it should fail to receive support from said spring.

3. A drilling-machine combining a non-rotatable sleeve; a spindle journaled in said sleeve; a coiled-spring for counter-balancing said sleeve and spindle; a planar pull-equalizer intervening between said spring and said sleeve for rendering uniform and maintaining in the same plane the pull of said spring on said spindle; manual means for adjusting the normal tension of said spring; a rack carried by said sleeve; means cooperating with said rack for shifting said sleeve either quickly manually or slowly by power; and a safety-catch comprising a spring pressed pawl mounted directly on said sleeve to cooperate with a fixed rack for automatically arresting the fall of said spindle in case it should fail to receive support from said spring, whenever the power feeding means is disengaged.

In witness whereof, I hereunto subscribe my name.

DAVID C. KLAUSMEYER.
